UNITED STATES PATENT OFFICE.

JACKSON G. CROWDES, OF BOSTON, MASSACHUSETTS, ASSIGNOR TO CHARLES W. RUGG, OF BROOKLINE, MASSACHUSETTS.

GRATE.

No. 396,692.

Specification of Letters Patent.

Patented Aug. 18, 1908.

Application filed August 5, 1907. Serial No. 387,104.

To all whom it may concern:

Be it known that I, JACKSON G. CROWDES, of Boston, in the county of Suffolk and State of Massachusetts, have invented certain new and useful Improvements in Grates, of which the following is a specification.

My invention relates to new and useful improvements in grates and is especially adapted to burn fine screenings or other fuel.

The main object of my invention is to provide a hollow grate through which air may be forced under pressure to supply the necessary oxygen to insure perfect combustion.

Another object of my invention is to prevent the air from entering the ash pit and compel it to pass up through the fuel on the grate bars.

In the accompanying drawings which illustrate a construction embodying my invention, Figure 1 is an isometric view partly in section showing a portion of the grate with the walls of the furnace broken away; Fig. 2 is a side view of the lower portion of one of the grate bars broken in the center; Fig. 3 is a plan view of same; Fig. 4 is an end view of the upper portion of one of the grate bars; Fig. 5 is a plan view of the same; Fig. 6 is a side view of the same; Fig. 7 is a vertical central section through the upper portion of the grate bar; Fig. 8 is a perspective view partly in section of the lower part of the upper portion of a grate bar; Fig. 9 is a vertical sectional view taken on line 9—9 Fig. 2 looking in the direction of the arrow.

Like letters of reference refer to like parts throughout the several views.

A represents a furnace having the usual side walls A', A² and front A³ provided with the usual ash pit and wall A⁴, the other wall being entirely broken away for clearness.

B represents a pipe for forced drafts connecting with the air duct B' which is provided with bearings B² for the hollow journals C of the lower portions or bars D of the grate. The journal C of each bar is hollow and receives forced draft from slots C² which draft passes into the lower portion D of each grate bar and up and out through the upper portion or grate - sections hereinafter described, and into the fuel for the combustion thereof. The opposite end of each grate bar is provided with a journal E which fits into the usual bearing in the side wall of the furnace with a flange E² resting against said bearing. The lower portion D of each grate

bar has a flange C³ which rests against the air duct B' as shown, and beyond said flange are located a number of hollow chambers or sockets D⁵; each of which is open at the top and has an opening D² in its bottom. Each chamber is provided with downwardly inclined sides D² adapted to hold the upper portions F of each grate bar in place and with which the inclined sides d² d³ contact forming a tapering joint when the upper portion F of each grate bar is placed in position on the lower portion.

The grate is assembled by placing in each hollow chamber D⁵ the upper portion F with shoulders d' resting upon the flat surfaces D' of each chamber D⁵ and with the duct F' in alinement with the duct C⁴ through which forced draft enters through slot C⁵ registering with slot C² in the bearing B² of the duct B'. The duct F' also is in alinement with passages D⁴ connecting the hollow chambers D⁵ from end to end. When each upper portion F is placed in its chamber D⁵ the lug M of each upper portion F passes through the opening D²; the lug M is provided with two inwardly-turned flanges M' on which rests the sliding damper N provided with holes O and when it is desired to clean the grate the sliding damper N is moved to bring the holes O into alinement with the ports P of each upper portion F so that the grate may be cleaned by the forced draft into the ash pit and the damper is then moved back to close the ports P and thereby prevent the forced draft from entering the ash pit. Any suitable device may be used for operating the damper. These dampers also act as keys to hold the upper portions F in place.

Each upper portion F of the grate surfaces G is provided with openings K through which the forced air passes into the fuel. Between these surfaces are spaces L through which natural draft from the ash pit may pass up into the fuel for combustion. The lower portion D of each grate bar may be of any desired length and may be provided with any number of chambers D⁵ into which fits a corresponding number of upper portions F.

The air under pressure entering the air duct B' passes through the slots C² and C⁵ into the duct C⁴ and from there into the duct F' throughout the length of the grate, as the duct F' in each upper portion F is connected with the other ducts F' by passages D⁴ and the air under pressure passes from the ducts

F' into the chamber H of each upper portion F and out through openings K in the upper surfaces of each upper portion F to the fuel to supply the necessary oxygen for proper combustion. By this construction it will be seen that the forced draft must all pass up through the grate into the fuel and cannot pass down into the ash pit. In addition, natural draft may be employed and passes up through the fuel by means of the spaces L, as previously described, and also through ports P when the dampers are open and the forced draft cut off.

The grate may be rocked when desired by the lever E³ to which is pivotally connected the link E² to which in turn the arm E' of each lower portion D is pivotally connected. The grates may be locked stationary if desired.

Although I have particularly described my improved grate as adapted for use with forced draft, yet it will be understood that it may be used with natural draft to advantage.

Having thus described the nature of my invention and set forth a construction embodying the same, what I claim as new and desire to secure by Letters Patent of the United States is:

1. In a grate, a hollow grate-bar, an air-supply pipe communicating with said grate-bar, transverse partitions having apertures through the same dividing said grate-bar into a series of communicating sockets or chambers, and grate-sections seated in said sockets having ducts registering with the apertures in said partitions and provided with perforations in their upper faces leading from said ducts.

2. In a grate, a hollow grate-bar having a series of openings in its bottom, an air-supply pipe communicating with said grate-bar, grate-sections seated in said grate-bar having ducts in line with the passage through the grate-bar and provided with perforations in their upper faces leading from said ducts and said grate-sections also having ports leading from said ducts to the ash-pit, and lugs on the lower parts of said grate-sections extending through said openings in the bottom of the grate-bar.

3. In a grate, a hollow grate-bar having a series of openings in its bottom, an air-supply pipe communicating with said grate-bar, grate-sections seated in said grate-bar hav-

ing ducts in line with the passage through the grate-bar and provided with perforations in their upper faces leading from said ducts and said grate-sections also having ports leading from said ducts to the ash-pit, lugs on the lower parts of said grate-sections extending through said openings in the bottom of the grate-bar, and a damper controlling said ports.

4. In a grate, a hollow grate-bar having a series of openings in its bottom, an air-supply pipe communicating with said grate-bar, transverse partitions having apertures through the same located between said openings in the bottom of the grate-bar dividing the latter into a series of communicating sockets or chambers, grate-sections seated in said sockets having ducts registering with the apertures in said partitions and provided with perforations in their upper faces leading from said ducts and said grate-sections also having ports leading from said ducts to the ash-pit, and lugs on the lower parts of said grate-sections extending through said openings in the bottom of said grate-bar.

5. In a grate, a rotatable hollow grate-bar having a series of openings in its bottom, a hollow journal for said grate-bar communicating with the interior of the latter, a bearing for said journal, an air-supply pipe communicating with said journal, transverse partitions having apertures through the same located between said openings in the bottom of the grate-bar dividing the latter into a series of communicating sockets or chambers, grate-sections spaced apart to form passages through the grate seated in said sockets having ducts registering with the apertures in said partitions and provided with perforations in their upper faces leading from said ducts and said grate-sections also having ports leading from said ducts to the ash-pit, lugs on the lower parts of said grate-sections extending through said openings in the bottom of the grate-bar, a guide-way on the under side of said lugs, and a damper movable in said guide-way to control said ports.

In testimony whereof, I have signed my name to this specification in the presence of two subscribing witnesses, this 24th day of July A. D. 1907.

JACKSON G. CROWDES
